7 Claims. (Cl. 271—50)

The invention relates to sheet feeding apparatus and more particularly to an apparatus for producing a stream of partly lapping sheets.

The invention provides apparatus for use in producing a stream of partly lapping sheets and for feeding the stream to a machine for operating on the stream of sheets, which apparatus comprises feeding means for feeding the stream to the machine, a stop member in the path of the sheets operative, during movement of a first sheet, to hold back a succeeding sheet lapped with the first to an excessive amount, until the lap is reduced to the desired amount and then to release the second sheet to allow the two sheets to move together in lapping relation.

The invention further provides apparatus for feeding a succession of sheets in underlapping relation to a laminating machine comprising means to feed a succession of sheets along a feed path to the machine, a stop member movable into the feed path from below the feed path which member is operable to lift a first sheet which is passing over the member without stopping the feed of the first sheet and to stop the next succeeding sheet, with its leading edge below the said first sheet, means to move the stop member into and out of the feed path in synchronism with the feed of the sheets along the path whereby the stop member is moved into the path as a first sheet is passing over the member and is moved out of the path of the next succeeding sheet before the one sheet has moved completely past the stop member.

In one embodiment the feeding means is in two sections, one before and the other after the stop member in the path of the sheets, means being provided for rendering the first section ineffective while the stop member is holding back a sheet and to render this section effective when the stop member has released the sheet.

It is preferred that the section of the feeding means before the stop member in the path of the sheets comprises a conveyor to which the sheets are held by suction, means being provided to operate the suction only when the stop member has released the sheet.

The stop member may be moved into and out of the path of the sheet by means of a solenoid.

The movement of the stop member into and out of the path of the sheet may be controlled by a timing device driven by the machine whereby the amount of lapping of the sheets remains constant when the speed of the machine is varied.

Preferably there is a variable speed connection between the timing device and the machine whereby the amount of lapping may be varied.

The machine may be a machine for laminating a succession of sheets to a web as described in United States patent specification No. 714,335 now U. S. Patent No. 2,916,444.

A specific example of apparatus according to the invention for feeding sheets in underlapping relation to a laminating machine will now be described with reference to the accompanying drawing which is a side elevation of the machine embodying the sheet feed apparatus.

The laminating machine 10 comprises essentially two pressure rollers 11 and 12 which are spring urged to-

2

wards one another and a table 14. A succession of sheets in underlapping relation passing across the table 14 and an overlying web of backing paper (e.g. of plastic film or foil) are fed to the nip between the rollers 11 and 12.

The backing paper is fed downwardly from a supply roller which is not shown.

A pool of adhesive is maintained between the web of backing paper and the sheets adjacent the nip between the rollers 11 and 12 and as the sheets and the backing paper pass between the rollers, the sheets are laminated to the backing paper. It will be appreciated that as a pool of adhesive is maintained between the sheets and web, the sheets must be fed to the rollers in underlapping relation or the adhesive will leak out between the sheets.

The apparatus for feeding the sheets in underlapping relation to the rollers 11 and 12 will now be described. A supply of sheets are stacked on a table 15 and the height of the table 15 is adjustable, by means of a foot treadle or an electric motor.

Adjacent the table 15, there is a platform 16 formed by the surface of a perforated conveyor belt 17 which is taken round rollers 18, 19 and 20. At the machine end of the conveyor 17, there are a number of stop members 21, extending in a line across the machine transversely to the direction of the feed of the sheets. The stop members 21 are attached to the armature 22 of a solenoid 23 by means of a lever 24 pivoted at 25.

Below the perforated conveyor belt 17, there are a number of vacuum boxes 26, one box being associated with each stop member 21 and the vacuum boxes 26 are evacuated by means of a vacuum pump (not shown) operating through magnetically operated valves 29, there being one valve for each vacuum box 26.

The magnetic valves 29 and hence the evacuation of the vacuum boxes 26 and also the movement of the stop members 21 are controlled by a variable speed unit 32 which is driven from the main drive of the machine 10.

There are two rollers 30 and 31 to feed sheets over the table 14.

The operation of the apparatus for feeding sheets in underlapping relation to the machine will now be described.

A stack of sheets is placed on the table 15 and the top sheet of the stack is arranged to be level with the platform 16, using the foot treadle or electric motor. The top sheet of the stack is fed manually on to the platform 16 and is placed with its leading edge against the stop members 21. The unit 32 operates the solenoid 23 to retract the stop members 21 and at the same time operates the valves 29 to evacuate the vacuum boxes 26 so that the conveyor belt 17, which is driven continually by the machine, conveys the sheet on the platform 16 into the nip between the rollers 30 and 31 from whence the sheet is fed to the table 14 and into the laminating machine proper.

As soon as the sheet has passed into the nip between the rollers 30 and 31, the unit 32 moves the stop member 21 back into the position shown in the drawing where they are in the path of the sheets and the evacuating valve 29 is once again closed.

It will be appreciated that moving the stop members 21 into the feed path of the sheet will not stop the movement of a sheet which has already passed into the nip between the rollers 30 and 31.

As soon as the machine operator sees that the first sheet is moving into the machine he places a second sheet on the platform 16 in underlapping relation with the first sheet so that the second sheet abuts the stop members 21, and so soon as the first sheet has reached a position where the underlap between the sheet has been reduced to a predetermined amount, the unit 32 again operates to

move the stop members 21 out of the feed path and to evacuate the vacuum boxes 26.

The second sheet is now fed to the machine. It will be seen that the amount of underlap between the two sheets is controlled by the timing of the operation of the unit 32. By variation of the speed of the unit 32, the amount of underlap can be varied. Further, as the unit 32 is driven from the main drive of the main machine, the underlap between successive sheets will remain the same if the speed of the main machine is altered.

I claim:

1. In combination with a machine for operating on a stream of partly lapping sheets, means for feeding the stream to the machine, means defining a path for the stream of sheets so fed, a stop member movable into and out of the path and operable when in the path to hold back a sheet lying intermediate in the stream and means operating in timed relation with the feeding means to move the stop member into the path behind the front edge of each sheet in turn to hold back the next sheet and out of the path when that edge has advanced a predetermined distance from the stop member and from the sheet so held back, said distance being of such a magnitude that the rear end of said first sheet is lapped over the front edge of the sheet so held back when the stop member is withdrawn.

2. In combination with a machine for laminating a stream of partly underlapping sheets, means for feeding the stream to the machine, means defining a path for the stream of sheets so fed, a stop member movable into and out of the path and operable when in the path to hold back a sheet lying intermediately in the stream and means operating in timed relation with the feeding means to move the stop member into the path from below the feed path behind the front edge of each sheet in turn to hold back the next sheet and out of the path when that edge has advanced a predetermined distance from the stop member and from the sheet so held back said distance being of such a magnitude that the rear end of said first sheet is lapped over the front edge of the sheet so held back when the stop member is withdrawn.

3. In combination with a machine for laminating a stream of partly underlapping sheets, means for feeding the stream to the machine, means defining a path for the stream of sheets so fed, a stop member movable into and out of the path and operable when in the path to hold back a sheet lying intermediate in the stream and means operating in timed relation with the feeding means to move the stop member into the path from below the feed path behind the front edge of each sheet in turn to hold back the next sheet and out of the path when that edge has advanced a predetermined distance from the stop member and from the sheet so held back, said feeding means being in two sections, one before and the other after the stop member in the path of the sheets, the section before the stop member having means which render the section effective only when the stop member is out of the path of the sheets.

4. In combination with a machine for laminating a stream of partly underlapping sheets, means for feeding the stream to the machine, means defining a path for the stream of sheets so fed, a stop member movable into and out of the path and operable when in the path to hold back a sheet lying intermediate in the stream and means operating in timed relation with the feeding means to move

the stop member into the path from below the feed path behind the front edge of each sheet in turn to hold back the next sheet and out of the path when that edge has advanced a predetermined distance from the stop member and from the sheet so held back, said feeding means being in two sections, one before and the other after the stop member, the section before the stop member comprising a conveyor and suction means which hold the sheets to the conveyor and which render the section effective only when the stop member is out of the path of the sheet.

10 5. In combination with a machine for laminating a stream of partly underlapping sheets, means for feeding the stream to the machine, means defining a path for the stream of sheets so fed, a stop member movable into and out of the path and operable when in the path to hold back a sheet lying intermediate in the stream and means operating in timed relation with the feeding means to move the stop member into the path from below the feed path behind the front edge of each sheet in turn to hold back the next sheet and out of the path when that edge has advanced a predetermined distance from the stop member and from the sheet so held back, and a solenoid which moves the stop member into and out of the path of the sheet.

15 20 6. In combination with a machine for laminating a stream of partly underlapping sheets, means for feeding the stream to the machine, means defining a path for the stream of sheets so fed, a stop member movable into and out of the path and operable when in the path to hold back a sheet lying intermediate in the stream and means operating in timed relation with the feeding means to move the stop member into the path from below the feed path behind the front edge of each sheet in turn to hold back the next sheet and out of the path when that edge has advanced a predetermined distance from the stop member and from the sheet so held back, and means for varying the predetermined distance aforesaid.

25 30 35 7. In combination with a roller machine for laminating a stream of partly underlapping sheets, means for feeding the stream to the machine, means defining a path for the stream of sheets so fed, a stop member movable into and out of the path and operable when in the path to hold back a sheet lying intermediate in the stream, a solenoid operable to move the stop member into the path from below the feed path behind the front edge of each sheet in turn and out of the path when that edge has advanced a predetermined distance from the stop member, switch means controlling operation of the solenoid, means for operating the switch and a variable speed drive from the machine to the switch operating means, the feeding means being in two sections, one before and the other after the stop member, the section before the stop member comprising a conveyor and suction means operable to hold the sheets to the conveyor to render the section effective, only when the stop member is out of the path of the sheets.
